UNITED STATES PATENT OFFICE.

EDWARD J. KLOUS, OF BROOKLINE, MASSACHUSETTS.

ATTACHMENT FOR ELECTRIC-LIGHT SWITCHES.

Application filed June 25, 1927. Serial No. 201,360.

This invention relates to attachments for electric switches and more particularly to removable extensions for the thimble of a universal, chain type electric light switch. The principal object of the invention is the provision of a simple and economical device adapted to be quickly and easily applied to the projecting thimble of a ceiling light switch of the aforesaid character and to serve as an extended lever of such length that a cord or chain secured to the outer end of the lever will hang vertically without contacting with the light globe.

The so-called universal type of chain switch having an outwardly extending operative thimble actuated by pulling or tilting the thimble or by pulling a connected cord or chain in any desired direction is well known and has been provided in large and increasing quantities as a convenient electric lighting switch for ceiling lights. In the usual type of ceiling fixture, however, the light globe is of such large diameter that its periphery projects horizontally beyond the vertical plane of the switch thimble, so that the cord or chain depending from the thimble hangs angularly in contact with at least one edge of the globe. Consequently, when the cord is pulled to actuate the switch, it is drawn across the globe edge and, if the globe is of the usual chain supported swinging type, causes the globe to swing pendulum-like, thus creating a flickering effect of the diffused light and frequently so loosening the globe fastenings that the globe falls to the floor. In order to obviate these disadvantages, I have devised an attachment which will permit the pull cord to hang freely at such distance from the edge of the light globe that objectionable contact between the cord and globe, when the cord is pulled, is avoided.

A recommended embodiment of the invention is illustrated in the accompanying drawings, in which:

Fig. 1 is a side elevation of a ceiling light fixture showing the improved device attached to the switch in operative position;

Fig. 2 is an enlarged section on the line 2—2 of Fig. 1;

Fig. 3 is a plan view, partly in section, of the attachment; and

Fig. 4 is an enlarged section through the device on the line 4—4 of Fig. 1.

Fig. 1 shows a conventional type of stationary ceiling fixture having a base 5, a

globe support 6 and a glass globe 7. The disposition of the usual form of universal switch 8 having the operative thimble 9 projecting laterally from the base 5 and provided with a pull chain 10 is best shown in Fig. 2. It will be understood that the switch may be operated either by a direct outward pull upon the thimble or by tilting the thimble in any direction with respect to its normal axis.

Attached to the thimble 9 is a metal rod or lever having a tubular end 11 fitting over the thimble. The outwardly extending portion 12 of the lever may be of any desired size or shape, but is preferably of reduced size and semi-tubular, as shown, to lessen its weight. A hole 13 may be provided at the outer end of the device for the convenient attachment of a cord 14, for example, as shown in Fig. 4. The length of the lever is such that it overhangs the light globe so that the cord hangs vertically at an appreciable distance from the outermost edge 15 of the globe.

The lever is preferably secured upon the thimble 9 by the thimble chain 10 which is retracted slightly and slipped into a slot 16 provided in the tubular socket portion 11. The beaded chain may then be cut off so that its end bead 17 engages the outer surface of the tubular socket at the inner end of the slot, thereby holding the attachment in position by reason of the chain tension.

An attachment constructed as above described simplifies the operation of the switch, for a relatively slight pull, either downward or outward from the globe, will actuate the thimble 9 without causing the cord 14 to strike the globe. The device may be made at reasonable cost of such size that it will fit any usual type of switch thimble and will have sufficient overhang above the light globe and may be attached and removed by simple hand operations. It will be understood, however, that details of construction may be varied without departing from the spirit of this invention, as defined in the following claims.

I claim:

1. An attachment for electric light fixtures of the ceiling type and having a projecting operative switch thimble of universal movement, consisting of a rigid, elongate member having a socket portion removably secured to the switch thimble, and a pull cord attached to the outer end of said

member, said cord hanging perpendicularly at a distance from the periphery of the light globe, whereby the cord will not contact with the globe when pulled downwardly.

5 2. An attachment for electric light fixtures of the ceiling type and having a projecting operative switch thimble of universal movement, consisting of a rigid, elongate lever having a tubular socket portion fitting over said thimble and being removably secured thereto, and a pull cord attached to the outer end of said lever, said cord hanging perpendicularly at a distance from the periphery of the light globe, whereby the 10 cord will not contact with the globe when pulled downwardly.

3. An attachment for electric light fixtures of the ceiling type and having a projecting operative switch thimble of universal movement, consisting of a rigid, metal lever overhanging the light globe and having a tubular socket portion fitting over said thimble, said tubular portion having a longitudinal slot extending toward its outer 15 end and the thimble having a pull chain engaging said slot under tension, thereby securing the socket upon the thimble, and a

pull cord attached to the outer end of said lever, said pull cord hanging perpendicularly at a distance from the periphery of the light globe, whereby the cord will not contact with the globe when pulled downwardly.

4. An attachment for electric light fixtures of the ceiling type and having a projecting operative switch thimble of universal movement, consisting of a rigid metal lever overhanging the light globe, said lever comprising a tubular socket portion, longer than the projecting thimble, fitting over said thimble, and a semi-tubular outer portion, said tubular portion having a longitudinal slot extending toward its outer end and the thimble having a pull chain engaging said slot under tension, thereby securing the 45 socket upon the thimble, and a pull cord attached to the outer end of said lever, said pull cord hanging perpendicularly at a distance from the periphery of the light globe, whereby the cord will not contact with the 50 globe when pulled downwardly.

Signed by me at Boston, Massachusetts,
this 23rd day of June, 1927.

EDWARD J. KLOUS.
